UNITED STATES PATENT OFFICE.

DELBERT E. BARTON, OF RACINE, WISCONSIN.

SELF-LOCKING SPRINGLESS HOOK.

SPECIFICATION forming part of Letters Patent No. 703,368, dated July 1, 1902.

Application filed July 27, 1901. Serial No. 69,912. (No model.)

To all whom it may concern:

Be it known that I, DELBERT E. BARTON, a citizen of the United States, residing at Racine, in the county of Racine and State of Wisconsin, have invented certain new and useful Improvements in Self-Locking Springless Hooks; and I do hereby declare the following to be a full, clear, and exact description of the invention, such as will enable others skilled in the art to which it appertains to make and use the same.

My present invention has for its object to provide an improved hook which will work without a spring of any kind and which will have a positive locking action.

To the above ends the invention consists of the novel devices and combinations of devices hereinafter described, and defined in the claims.

In a general way it may be stated that my improved hook is intended for use where so-called "spring snap-hooks" are now generally employed, although in view of its positive locking action it will be serviceable where the spring-hooks will not satisfactorily serve the purpose.

My improved hook is illustrated in the accompanying drawings, wherein like characters indicate like parts throughout the several views.

Figure 1 is a view in side elevation showing one of my improved hooks applied to the trolley-head of an electric car. Figs. 2, 3, and 4 are details in side elevation showing the component parts of the hook separated. Fig. 5 is a view corresponding to Fig. 1, but showing the hook as detached from a trolley-pole head; and Fig. 6 is a vertical section approximately on the line $x^6 x^6$ of Fig. 1, some parts being shown in full.

The numeral 1 indicates a trolley-pole, having an ordinary head 2, to which the trolley-wheel 3 is journaled. As is usual, the said head 2 is provided with an eye 4, to which usually the spring snap-hook of the trolley-rope or the end of the trolley-rope itself is attached.

In its most approved form my improved hook is made up of an external annular member a , having a hook a' and a bulged notch portion a^2 , which parts a' and a^2 stand diametrically opposite to each other. A coöp-

erating internal disk-like member b , which is formed in two parts secured by rivets or otherwise after the parts are put together, 55 works pivotally within the member a . One of the members b is provided with a segmental or broken lock-flange b' , and both thereof are provided with coincident lock-notches b^2 and with peripheral flanges b^3 , which flanges 60 b^3 embrace the sides of the said member a . The notch a^2 in the member a is relatively shallow as compared with the notch b^2 in the member b , this being for an important purpose hereinafter to be noted. The hook a' 65 projects laterally from the member a and works just outward of the edge of the lock-flange b' of the member b . The trolley-rope f is looped at its upper end f' , and this loop is passed through the notch b^2 of the member 70 b . When the notch b^2 of the member b registers with the notch a^2 of the member a , the lock-flange b' is held in a position to lock the hook. When, however, the said member b is turned with respect to the member a , (see 75 Fig. 5,) the flange b' is turned away from the hook a' , and the hook may then be applied to and removed from working position. The diameter of the rope which forms the loop f' is such that when it lies in the relatively 80 shallow notch a^2 of the member a it will stand in the path of movement of the peripheral portions of the member b , the one with respect to the other. When, however, the loop f' is forced into the relatively deep notch b^2 85 of said member b , it will clear the inner portion of the annular member a , so that the said member b may be freely rotated to unlock the hook.

The downward-pulling strain on the rope 90 f when the trolley is pulled downward or the weight of the rope itself when it hangs loose keeps the loop f' in engagement with the notch a^2 , and thus locks the members a and b against rotation, or at least against such rotation as would be required to throw the lock-flange b' into a releasing position. The said lock-flange b' may be extended through a very much greater segment, thereby increasing the oscillation required to release the 100 hook.

The device is, as is obvious, capable of considerable modification within the scope of my invention. Its range of use is very large.

Its application to a trolley-pole illustrates only one of its many uses. It will serve in a most satisfactory manner as a tug-hook for harnesses, for instance, and in this use of the 5 device where the draft strains are horizontal and the tugs are normally permitted to sag it would be important to extend the lock-flange through a very much greater arc of a circle than that illustrated in the drawings.

10 The hook always affords a positive lock in that it cannot be opened or closed by lateral movements or strains put upon the same by the device to which it is attached or otherwise.

15 Of course the trolley-rope is only one of the many forms of connections which may be applied to the members of the hook. Hence I use the term "draft connection" broadly to include all forms of connections—such as the 20 trolley-rope, tugs, lines, or other devices which may be applied to the pivotally-connected members.

What I claim, and desire to secure by Letters Patent of the United States, is as follows:

25 1. The combination with a pair of pivotally-connected members having coöperating lock-notches and the one having a hook and the other having a coöperating lock-flange, of a 30 draft connection having interlocking engagement with the lock-notches of said members when said lock-notches are registered and normally serving to positively lock said members against rotation, the one with respect to 35 the other, substantially as described.

2. The combination with the external member *a* having the hook *a'*, of the internal member working pivotally within said member *a* and provided with the lock-flange *b'* and notch *b*², and a draft connection applied 40 within said notch *b*² and normally holding said lock-flange *b'* and hook *a'* in locking relations, substantially as described.

3. A pair of pivotally-connected members having coöperating locking parts, said members having coöperating relatively shallow and deep lock-notches, adapted to register when said locking parts are in locking positions, and a draft connection applied to said members and working in said lock-notches, 45 which draft connection is normally held in said shallow lock-notch, to lock said members against rotation and is movable into said deep lock-notch to unlock said members, substantially as described.

4. The combination with an annular exterior member, of disk-like interior members rotatively mounted therein, one member having a hook and the other a coöperating lock-flange, and a draft connection applied to said 50 interior member and normally serving to hold said hook and lock-flange in locking relations, substantially as described.

In testimony whereof I affix my signature in presence of two witnesses.

DELBERT E. BARTON.
